INSULATED COMBINED FOOD HOLDER AND SERVING TRAY

Wayne W. Beaubian, 1410 Civic Center Drive,
East Brunswick, N.J. 08816

Filed Apr. 17, 1974, Ser. No. 461,490

Term of patent 14 years

Int. Cl. D9—03

U.S. Cl. D7—77

Fig. 1.

Fig. 2.

Fig. 3.

FIG. 1 is a perspective view of an insulated combined food holder and serving tray showing my new design;

FIG. 2 is a front elevational view;

FIG. 3 is a side elevational view;

FIG. 4 is a perspective view of the top portion shown in an inverted position;

FIG. 5 is a perspective view of the bottom portion.

I claim:

The ornamental design for an insulated combined food holder and serving tray, substantially as shown and described.
